(57) **CLAIM**

The ornamental design for rope figure toy, as shown and described.

DESCRIPTION

FIG. 1 is a front perspective view of a rope figure toy, showing my new design;

FIG. 2 is a left side elevational view thereof; and,

FIG. 3 is a rear perspective view thereof.

The portions of the rope figure toy that are not shown in the drawings do not form a part of the claimed design.

1 Claim, 3 Drawing Sheets**FIG. 1.**

FIG. 2.

FIG. 3.
